BUCKLE FASTENER DEVICE

William A. Bedford, Jr., Hingham, Mass., assignor
to United-Carr Fastener Corporation, Cambridge, Mass., a corporation of Massachusetts

Application February 13, 1946, Serial No. 647,228

1. Claim. (Cl. 24—77)

1

The present invention relates to improvements in buckles and particularly to the type of buckle having end slots adjustably receiving one end of a strap or belt and which provides an attaching means whereby an opposite end portion of the strap or belt is secured to the buckle.

Buckles of the type having strap-receiving slots with strap-gripping prongs extending from an edge of one of the slots have been in common use for a long time. This form of buckle has certain inherent objections which the present invention is intended to overcome. Thus the buckle must be attached to a strap end in a predetermined manner to place the pronged slot in proper relative position to enable the prongs to grip the strap. Also in adjusting this form of buckle on a strap, it is necessary to unloosen the strap to enable it to feed freely through the pronged slot after which it must be pulled taut before it can be determined whether the buckle is disposed in desired position along the length of the strap. This operation may have to be repeated one or more times before the buckle is correctly positioned on the strap. In addition the prongs which in most instances are designed to penetrate completely the strap tend to tear or fray certain forms of strap material after repeated adjustment of the buckle.

The main purpose of the present invention is to effect a buckle device which will overcome the objections mentioned in connection with older types of buckles of the class described.

One of the objects of this invention is to provide a buckle which may normally be adjusted relative to the strap end to which it is attached by simply sliding the buckle freely to the desired position, but which at the same time grips automatically the strap when the strap is subjected to strains tending to unloosen it.

Another object of the invention is the provision of a buckle having strap-gripping means which is constructed so that the strap end may be received through the slot at either end of the buckle in initially attaching the buckle to the strap.

A further object of the invention is to provide a buckle having a strap-gripping means adapted to engage the strap by a wedging action whereby the material of the strap is less abused than when the strap is penetrated by prongs as in the older form of buckle.

Other aims and objects of the invention will be apparent to those skilled in the art from a consideration of the accompanying drawings and annexed specification illustrating and describing a preferred embodiment of my invention.

2

In the drawing:

Fig. 1 is a rear view of a preferred embodiment of my improved buckle with one end of a strap attached thereto;

Fig. 2 is a front elevation of my improved buckle, the strap end to which it is being attached being broken away to show the construction of the buckle member;

Fig. 3 is a view similar to Fig. 2 and showing operation of the buckle to grip the strap end when the strap is subjected to strains in predetermined directions;

Fig. 4 is a sectional view taken along the line 4—4 of Fig. 2;

Fig. 5 is an exploded view showing parts partially in section;

Fig. 6 is a front elevation of the gripping element forming a part of my buckle member;

Fig. 7 is a side elevation of the element shown in Fig. 6;

Fig. 8 is a section view taken along line 8—8 of Fig. 1; and

Fig. 9 is a section similar to Fig. 8 showing the manner in which the buckle operates to grip a strap.

Referring to the drawing, I have shown my improved buckle member 1 attached to an end 2 of a strap or belt. Referring specifically to the form of buckle member illustrated in Figs. 1-3, the buckle comprises a generally flat frame having end portions 4 and 5 and a body portion 6 intermediate the end portions. The end portions 4 and 5 have elongated slots 7 and 8 respectively which receive the end 2 of the strap when the buckle is attached to the strap. The body portion 6 has an elongated opening 9 of predetermined length disposed substantially in the center of the body portion 6 with its major axis extending in a line substantially perpendicular to the major axes of the slots 7 and 8.

Assembled with the buckle frame is a strap-gripping means 10 which in my preferred embodiment comprises a gripping element 11 in the form of a circular disc having a serrated circumferential edge 12. The disc 11 normally lies on the front side of the buckle frame with its inner flat surface substantially adjacent the front surface 13 of the buckle frame. The diameter of the disc 11 is greater than the minor axis of the opening 9 and less than the distance between the inner edges 14 and 15 respectively of the slots 7 and 8 so that the circumferential edge of the disc terminates short of the edges 14 and 15 when the disc is in the normal position illustrated in Fig. 2. The disc 11 in the preferred embodiment of my inven-

tion has, as shown in Fig. 7, an integral shank 16 which is preferably drawn from the material of the disc and which extends outwardly on one side thereof. When the parts of the buckle are assembled the shank 16 extends through the opening 9 to the other side of the buckle frame from that upon which the disc 11 is disposed. The shank 16 is of smaller diameter than the minor axis of the opening 9 permitting the shank to move longitudinally of the opening 9 causing the disc 11 to slide in a plane substantially parallel to the front surface 13 (Figs. 2 and 3) of the body portion 6 for a purpose to be described. The strap-gripping means provides on the opposite side of the buckle frame from the disc 11 an attaching means enabling the opposite end 17 of the strap to be attached to the strap-gripping means. In the preferred embodiment of my invention the attaching means is in the form of a stud member 18 having a base portion 19 and a hollow stud head 20 drawn therefrom so as to extend outwardly from the buckle frame when the parts are in complete assembly. The attaching means may be secured to the disc element in any suitable manner, but in my preferred embodiment I have chosen to accomplish this by upsetting the outer end 21 of the shank 16 within the hollow head 20 of the stud member as illustrated in Fig. 8. The base portion 19 of the stud member is of greater diameter than the minor axis of the opening 9 whereby the base 19 which is disposed substantially adjacent the rear surface 22 (Fig. 4) of the buckle frame cooperates with the disc element to secure the strap-gripping means in assembly with the buckle frame.

The opposite end 17 of the strap carries a snap fastener socket member 23 for cooperative fastener engagement with the stud member 18 to attach the strap end 17 to the strap-gripping means 10. The socket member 23, the construction of which forms no part of my present invention, provides resilient segments 24 adjacent a stud-receiving opening 25. The segments 24 expand and contract to engage the stud head 20 upon application of the stud head into the opening 25 as will be understood by those skilled in the art. The socket 23 is secured to the strap end 17 by any suitable means such as an attaching member 26 which, as shown in Fig. 8, has a ring element 27 disposed on one surface of the strap end 17. The ring 27 provides prong elements 28 which extend from the inner edge of the ring 27 through the material of the strap end 17 and are deformed within an annular apron 29 provided by the socket 23.

In operation of my buckle member in connection with a strap in the form of a belt and the like, the strap end 2 is threaded through the slots 7 and 8 of the buckle 1, it being immaterial into which slot the strap is first entered, and the strap end 17 is moved around the body of the wearer and secured to the buckle member by engaging the socket 23 with the stud member 18. If it is necessary to loosen or tighten the strap this may be accomplished by simply grasping the strap end 2 with one hand and moving the buckle 1 with the other hand to desired position with respect to the strap end 2. In adjusting the buckle in this manner movement of the strap through the slots tends to maintain the disc element 11 in normal centered position with relation to the body portion 6 of the buckle frame as illustrated in Figs. 2, 4 and 8. In view of this fact during adjustment of the buckle the circumferential edge 12 of the disc element 11 is restrained from projecting beyond the

inner edges 14 and 15 of the strap-receiving slots 7 and 8 and the strap is movable freely through the slots 7 and 8 until the desired tightness or looseness of the belt is effected.

5 The gripping or locking action upon the strap tending to hold the buckle securely in adjusting position, to which advantage my improved buckle is directed, if effected by means of engagement of the disc element with the strap when 10 strains are exerted on the strap ends in directions tending to unloosen the strap. Thus with reference to Figs. 3 and 9 of the drawing, when the strap end 17 is pulled in the direction of the arrow A a strain is exerted upon the strap end 2 in the direction of the arrow B. As a result 15 of these strains the disc element 11 will move beyond the edge 15 of the slot 8 to engage its circumferential edge 12 with the strap end 2 thereby tending to wedge the portion 31 of the 20 strap against the outer edge 30 of the slot 8 (Fig. 9). At the same time as a result of the strain upon the strap end 2 in the direction of the arrow B when unloosening forces are exerted the wedging action tends to move the portion 31 of the 25 strap into a position substantially normal to that portion 32 of the strap covering the front of the buckle frame. The relatively sharp angle taken by the strap portions 32 and 31 as a result of engagement of the strap by the gripping element 11 reduces the opportunity for the strap end 2 to move through the slot 8 when the locking 30 action is applied. The mechanical action by which the disc element 11 is moved into locking engagement with the strap end 2 is effected 35 through the strain exerted on the strap end 17 in the direction of the arrow A. This force is transmitted through the socket 23 to the stud member 10 engaged therewith which in turn shifts the shank element 16 longitudinally of the 40 slot to dispose the disc element 11 in strap-engaging position. While the buckle is operable to grip tightly the strap without the necessity of serrating the circumferential edge of the disc element it is deemed desirable to provide very short 45 teeth on the disc edge causing the edge to embed itself slightly within the fibers of the inner surface of the strap thereby enhancing the gripping action.

While I have illustrated my invention as applied to a belt-like structure in which the buckle is secured to one end of a strap and the cooperating fastener means to another end, it is understood that the buckle would be completely operable in an installation in which the buckle was secured to a piece of material such as an overall bib for securing a shoulder strap. In an application of this type the strap-gripping means must be attached to the bib in any suitable manner to operate to grip the strap when strains are exerted upon the strap or bib tending to alter the relative positions of the strap end and buckle.

Although I have illustrated and described a preferred embodiment of my invention, I do not wish to be limited thereby as the scope of my invention is best defined by the following claim.

I claim:

A fastener device comprising a buckle frame having spaced strap-receiving slots and a body portion intermediate said slots, said body portion having an opening and a flat bearing surface surrounding said opening, a movable flat disc-shaped strap-gripping element of greater diameter than said opening in said body portion disposed on one side of said body portion in sliding contact with said flat bearing surface, a fas-

tener member movable with the strap-gripping element and disposed on the opposite side of said body portion in slidable bearing engagement therewith, an attaching element extending through said opening for rotatably mounting and assembling said gripping element and fastener member on said frame, said opening being of larger area than the cross-sectional area of said fastener-attaching element where it passes through said opening to permit shifting of said strap-gripping element over either strap-receiving slot and into biting engagement with a strap threaded therethrough substantially in the plane of said bearing surfaces, and said fastener member having a flat disc-shaped portion of substantially larger dimension than a minor dimension of said opening to slidably bear on one face of said buckle frame to retain a peripheral edge portion of said strap-gripping element in

20

slidable bearing engagement with the opposite face of said buckle frame.
